UNITED STATES PATENT OFFICE.

PATRICK J. DELANEY, OF SHENANDOAH, PENNSYLVANIA.

HOLDER FOR CLEANSING INSTRUMENTS.

1,357,963.

Specification of Letters Patent. Patented Nov. 9, 1920.

Application filed June 16, 1920. Serial No. 389,436.

To all whom it may concern:

Be it known that I, PATRICK J. DELANEY, a citizen of the United States, residing at Shenandoah, in the county of Schuylkill and 5 State of Pennsylvania, have invented new and useful Improvements in Holders for Cleansing Instruments, of which the following is a specification.

This invention relates to a holder for 10 cleansing instruments, and the main object of the invention is to provide a combination holder for a scrubbing brush or dust brush, a drier or polisher, squeegee, or the like, whereby such cleansing devices may 15 be readily and conveniently employed upon a single holder.

A further object of the invention is to 20 provide a handle type of holder in the form of a clamping head provided with a handle 20 adjustably connected therewith, whereby the head and handle may be set at different working angles, said head having clamping devices for holding the several cleansing implements so that the same may be 25 employed in a ready and convenient manner.

The invention consists of the features of 30 construction, combination and arrangement of parts, hereinafter fully described and claimed, reference being had to the accompanying drawings, in which:

Figure 1 is a side elevation of a combination holder of the character described embodying my invention.

Fig. 2 is an end elevation of the same.

Fig. 3 is a vertical transverse section 35 through the holder taken about centrally thereof.

Fig. 4 is a top plan view of the holder with the drier or polisher removed.

Fig. 5 is a bottom plan view of the holder 40 with the brush removed.

Fig. 6 is a detail view showing the adjustable connection of the handle with the holder or clamping head.

In the practical embodiment of my invention, I provide a holder or clamping head 1 45 consisting of a main bracket formed to provide a base plate 2 having an upturned portion or inner side plate 3 and a centrally disposed plate 4 arranged in parallel relation to the plate 3. The said main bracket member is also provided with a vertically

disposed front side plate 5 extending above and below the base plate 2.

The upper portion of the plate 4 provides 55 one of a pair of jaws for clamping and holding a drier or polisher 6 in position, the other or complementary jaw being formed by a plate 7 arranged in parallel relation to the plate 4 and having an outwardly extending base flange 8 reinforced therefrom by braces 9. The flange 8 is fitted to slide upon a guide plate or shelf 10 extending inwardly from the upper portion of the side plate 5 and terminating at its inner end in 60 a downturned flange 11 which is arranged to bear against the base plate 2 and lower portion of the plate 4. The jaw member 4 is fixed with relation to the jaw member 7, the latter being adjustable toward and from 70 said jaw member 4 to firmly clamp the drier or polisher 6 between said jaws and to enable driers or polishers of different thicknesses to be clamped with equal facility. The respective members 3, 4 and 7 are provided 75 with openings for the passage of screws 12, which may turn loosely in the openings in the members 3 and 4 and have a threaded engagement with the member 7, whereby the last-named member may be adjusted toward and from the member 4, nuts 13 engaging the screws for locking the jaws 80 in relatively adjusted position. As shown in the present instance the screws 12 are provided at their rear ends with winged 85 heads or finger-pieces 14 whereby they may be conveniently manipulated. The drying or polishing element 6 may consist of a strip of felt, rubber or other suitable material of any of the various kinds employed for drying or polishing floors, walls, glass or other surfaces, and the mode of use thereof will 90 be readily understood from the subjoined description.

The lower portion of the side piece 5 is 95 provided with an inturned lower end and forms a fixed clamping jaw 15 to engage one side of a brush head. The opposite side of the brush head is adapted to be engaged by a hooked complementary jaw 16 100 carried by a vertically disposed bracket plate 17 which extends upwardly on the outer or rear side of and parallel with the plate 3, which plate 3 is connected with

the plate 4 by braces 18 whereby such portions are braced and reinforced. A jaw 16 is adjustable with relation to the jaw 15 for the purpose of clamping or releasing 5 the head of the brush 19, which may be a scrubbing brush, a dust brush, or any other similar kind of a brush. Projecting inwardly from the bracket 17 are guide arms 20 which underlie the base plate 2 10 and are provided with slots 21 slidably engaging headed pins or studs 22 on the base plate, whereby the jaw 16 and bracket 17 are slidably mounted for adjustment on the main bracket, the bracket plate 17, the side 15 piece 3, the plate 4 and the portion 11 of the side piece 5 are provided with openings for the passage of adjusting screws 23 whereby the jaw 16 may be adjusted inwardly and outwardly, said screws having 20 winged heads or finger-pieces 24 for convenience in adjusting them, and said screws also having a threaded engagement with either or both of the parts 4 and 11 for adjusting purposes and being fitted with 25 lock nuts 24 whereby they may be secured in adjusted position to hold the jaw elements 15 and 16 after adjustment in fixed relationship. It will thus be understood that a scrubbing brush, dusting brush or 30 other like brush may be secured in position upon the holder or clamping head for use as may be required in various washing or cleansing operations, that this brush may be used in combination with the element 35 6 for successive or alternate washing or brushing and drying or polishing operations by simply inverting or reversing the position of these parts by properly manipulating the clamping head during the various operations described.

Fixed to the side plate 3 is a bracket segment 25, to which is pivotally mounted, as at 26, the fork arms 27 of a socket 28 in which is secured the lower end of an operating handle 29. Surrounding this socket member 28 is a band or sleeve 30, which is loosely held in position by a suitable fastening 31 and is apertured for the passage of a bolt 32 carrying a wing nut 33 adapted 50 to be adjusted to hold the sleeve from pivotal movement. The sleeve has a projection 34 forming a pawl or dog to engage locking teeth or notches 35 in the bracket 25 whereby the handle may be locked to 55 the holder at different working angles, thus adapting the various cleansing elements to be disposed at the most convenient angles for use in the manipulation of the device.

From the foregoing description, taken in 60 connection with the accompanying drawings, it will be seen that my invention provides a clamping device or head whereby a number of cleansing and drying or polishing devices may be carried for ready and 65 convenient use as occasion may require, it

being only necessary to properly adjust the handle or to hold the implement in different positions in order to bring any one of the cleansing or polishing devices into proper position for use. Other advantages 70 of the invention will be apparent from the foregoing description.

Having thus fully described my invention, I claim:

1. A device of the character described 75 comprising a base plate having stationary jaws projecting from opposite sides thereof, adjustable jaws arranged for co-operation with said stationary jaws, cleansing elements held between the respective sets 80 of jaws, and means for adjusting the adjustable jaws independently of each other.

2. A device of the character described comprising a base plate, a stationary jaw carried by the base plate and projecting from one side thereof, a supporting seat on said side of the base plate, a second stationary jaw carried by said clamping plate and projecting from the opposite side thereof, a movable jaw slidably engaging said seat and adjustable toward and from the first-named stationary jaw, a cleansing element clamped between said jaws, a second jaw 90 slidably engaging the base plate for co-operation with the second-named stationary 95 jaw, a cleansing element adapted to be held between the latter-named jaws, and sets of devices for respectively adjusting the adjustable jaws.

3. A device of the character described 100 comprising a base plate, a side plate integral with said base plate and projecting upwardly therefrom, a stationary jaw extending upwardly from the base plate parallel with said side plate, a second side plate projecting above and below the base plate and having its downwardly projecting portion forming a second stationary jaw and its upwardly projecting portion forming a supporting seat, an adjustable jaw slidably engaging said supporting seat and movable toward and from the first-named stationary jaw, a second adjustable jaw co-operating with said second stationary jaw, and means for adjusting said adjustable jaws.

4. A device of the character described 110 comprising a bracket member presenting a base plate, fixed jaws projecting from opposite sides of said plate and a seat support on one side of the plate, a movable jaw slidably mounted on said seat support with relation to the fixed jaw on the same side of the base plate, a second movable jaw arranged for co-operation with the other fixed jaw, and adjusting screws carried by the 120 bracket member for adjusting said movable jaws.

5. A device of the character described 125 comprising a bracket member presenting a base plate, fixed jaws projecting from oppo- 130

site sides of said plate and a seat support on one side of the plate, said plate also having a side piece parallel with the first-named fixed jaw, a movable jaw slidably mounted on said seat support with relation to the fixed jaw on the same side of the base plate, a second movable jaw arranged

for coöperation with the other fixed jaw, and adjusting screws for adjusting said movable jaws, said screws extending 10 through said side piece.

In testimony whereof I affix my signature.

PATRICK J. DELANEY.
